GAS MILEAGE CALCULATOR

Yehuda A. Konnan, North Palm Beach, Fla., assignor to
Wykon Inc., Riviera Beach, Fla.

Filed July 18, 1973, Ser. No. 380,374

Term of patent 14 years

Int. Cl. D19—99

U.S. Cl. D64—11 B

FIG. 1 is a front elevational view of a gas mileage calculator showing my new design;

FIG. 2 is a left edge elevational view; and

FIG. 3 is a right edge elevational view.

The back view of the gas mileage calculator is conventional and unornamented except for the eyelets.

I claim:

The ornamental design for a gas mileage calculator, substantially as shown and described.
